MALCOLM W. QUIGGLE AND GILBERT E. BAILEY, OF LOS ANGELES, CALIFORNIA;
SAID BAILEY ASSIGNOR TO SAID QUIGGLE.

TIMED DETONATOR FOR EXPLOSIVES.

1,088,448.

Specification of Letters Patent.

Patented Feb. 24, 1914.

Application filed May 6, 1911. Serial No. 625,607.

To all whom it may concern:

Be it known that we, MALCOLM W. QUIGGLE and GILBERT E. BAILEY, citizens of the United States, both residing at Los Angeles, in the county of Los Angeles and State of California, have invented a new and useful Timed Detonator for Explosives, of which the following is a specification.

The object of our invention is to provide 10 a detonator for explosives which is ignited by heat generated from an electric current with means whereby a greater or less time will elapse during which the fire is communicated from the igniter to the detonating compound to explode the same.

Our invention consists in providing a detonator having a metallic casing, and a detonating compound therein with means for producing an initial ignition, and combustible means arranged between the means for producing the initial ignition and the detonating material whereby the transmission of fire from the ignition means to the detonating material may be regulated or 25 controlled to consume a greater or less degree of time as desired.

The accompanying drawings illustrate a preferred form of our invention, but other forms and materials will present themselves to those versed in the art.

Figure 1 is an enlarged perspective elevation of our timed detonator, showing the metal shell and electrical wires for connection with a source of electrical energy. Fig. 35 2 is an enlarged longitudinal section showing a preferred form of loading of the detonator.

1 is a metal shell which may be made of any desired shape or size.

40 2, 2 are wires adapted to be connected to a source of electrical energy, their ends 3, 3 being connected by a high resistance igniter wire 4.

5 is a body of fulminate of mercury or 45 any other suitable detonating compound.

In the detonator herewith illustrated we have shown as the means for regulating the communication of fire from the igniter wire 4 to the fulminate 5 a series of or sections 50 of an instantaneous burning material, such as pyroxylin, commonly known as soluble gun cotton indicated as at 6, 6', 6'', and having interspersed between such pyroxylin a slow burning material consisting of pyroxylin which has been dipped in and fully 55 saturated with camphor dissolved in alco-

hol and which has afterward been compressed to form the slow burning diaphragms 7, 7'.

8 is a paper tube, open at both ends, 60 which surrounds the pyroxylin and the slow burning diaphragms, such paper 8 having preferably been prepared to resist combustion by dipping the same in a solution of tungstate of soda, thereby preventing the 65 heat from the burning of one section of pyroxylin being transmitted to another section or body of that material through the heating of the walls of the metallic shell. The burning of the first body of pyroxylin 70 6 ignites the first diaphragm 7 of compressed and treated pyroxylin. On account of its slow burning characteristics the ignition of the second body of pyroxylin 6' is delayed for an appreciable length of time 75 or until the first diaphragm 7 has been burned and the fire communicated to the second section, which upon ignition is consumed practically instantaneously and ignites the second treated pyroxylin diaphragm 7' which after burning for an appreciable length of time ignites the third and last body of pyroxylin which instantly ignites the detonating material 5. A suitable cement 9 is used to close the open end 80 of the cap shell.

By employing one or more bodies of pyroxylin and one or more diaphragms of the slow burning composition, we are enabled to accurately time the final discharge of the 90 detonating material. This is especially necessary where several charges of explosives are ignited by a current from a single source of electrical energy or when a number of charges of explosives are discharged 95 in close proximity to one another as is necessary in mine work.

By increasing or decreasing the thickness of the slow burning material interspersed between the ignition means and the detonating material the length of time required to finally explode the same is varied, and in practice detonators of quicker or slower burning qualities are provided for use where a series of explosions are required, 105 as for example in rock work in mines. Ordinarily in such work a series of six or more holes are drilled and loaded for firing. For example, two of such holes are drilled at the foot of the wall, two holes are 110 drilled at a point approximately half way up the wall and two holes at the top of the

wall, and in ordinary practice the two center holes are fired first and the bottom holes are next fired, after which the top holes are fired, thereby allowing the center of the wall to be relieved or broken, the foot thereof next to be relieved, after which the full effect of the force of the explosives employed in the top holes is utilized. By providing detonators adapted to be ignited by 10 a single charge of electric current and which will burn within varying degrees of time, we are enabled to discharge a series of loaded holes sequentially and in the above manner and thereby accomplish the maximum amount of work from a minimum amount of explosives.

Other forms of detonators may be employed than that shown and other material or materials may be employed for transmitting the fire from the igniter to the detonating compound or mixture, but all such variations or changes whereby the lapse of an appreciable length of time occurs between the ignition and final explosion of a 25 cap detonator is secured is considered by us to be within the scope of our invention.

The means herein described for communicating the fire from the igniter to the detonating material has the distinguishing 30 characteristics of supporting its own combustion, igniting and burning without detonation or appreciable expansion. This is a desirable feature of our invention as the whole load of the exploder is contained 35 within a metallic cap and if a combustible material which detonates when ignited is employed there is danger that such explosion or expansion would cause the fulminate to be exploded before the time desired and 40 such explosion would also disrupt the metallic cap in advance of the fulminating material.

What we claim is:—

1. In a detonating exploder, a shell, a 45 body of detonating material in the shell, means for producing an initial ignition within the shell, a body interposed between the initial igniter and the detonating material comprising a section of a quick burning non-explosive material and a slow burning non-explosive material, substantially as set forth.

2. In a detonating exploder, a shell, a body of detonating material in the shell, 55 means for producing initial ignition within the shell, a body of pyroxylin arranged within the shell, a body of pyroxylin arranged to contact with the igniter, a body of compressed pyroxylin treated with camphor arranged between such pyroxylin and the detonating material whereby a material lapse of time is consumed in transmitting fire from the igniter to such detonating ma-

terial after the initial ignition is accomplished.

3. A detonating exploder comprising a metallic shell, a body of detonating material in the shell, means for producing an initial ignition within the shell, and a series of alternate slow and quick burning materials connecting said detonating material and said initial ignition means.

4. In a detonating exploder, a metallic shell, a heat insulating lining for the shell, a body of detonating material in the shell, 75 means for producing an initial ignition within the shell, a body interposed between the initial igniter and the detonating material comprising a section of a quick burning non-explosive material and a slow burning non-explosive material, substantially as set forth.

5. In a detonating exploder a metallic shell, a heat insulating lining for the shell, 85 a body of detonating material in the shell, means for producing an initial ignition within the shell, a body composed of a timed combustible non-explosive material arranged within the shell between the detonating material and the igniter, such 90 timed combustible material being arranged to take fire from the igniter and communicate the same to the detonating material.

6. In a detonating exploder, a metallic shell, a heat insulating lining for the shell, 95 a body of detonating material in the shell, electrical means for producing an initial ignition within the shell, a timed combustible non-explosive material arranged between the detonating material and the igniter and 100 adapted and arranged to conduct fire from such igniter to the detonating material.

7. In a detonating exploder, a containing member, a body of detonating material in 105 said member, a body of pyroxylin in contact with the detonating material, means for producing an initial ignition, a body of pyroxylin in contact with the igniter, and a body of compressed pyroxylin treated with camphor arranged between aforesaid bodies 110 of pyroxylin.

8. In a detonating exploder, a containing member, a body of detonating material in 115 said member, means for producing an initial ignition, and a body of pyroxylin treated with camphor between said body of detonating material and the initial ignition means.

In testimony whereof, we have hereunto set our hands at Los Angeles, California, this 28th day of April, 1911.

MALCOLM W. QUIGGLE.
GILBERT E. BAILEY.
